(57) CLAIM

The ornamental design for a football-shaped container, as shown and described.

DESCRIPTION

FIG. 1 is a top/right side view of the football-shaped container of our invention;

FIG. 2 is a front view of the football-shaped container;

FIG. 3 is a rear view of the football-shaped container;

FIG. 4 is a right side view of the football-shaped container;

FIG. 5 is a left side view of the football-shaped container;

FIG. 6 is a top view the football-shaped container;

FIG. 7 is a bottom view of the football-shaped container;

FIG. 8 is an exploded, right side view of the football-shaped container; and,

FIG. 9 is an exploded, right side perspective view of the football-shaped container.
